(57) **CLAIM**

The ornamental design for an aftermarket side window wiper design for a motor vehicle, as shown and described.

DESCRIPTION

FIG. 1 is a top, front, end view of an aftermarket side window wiper design for a motor vehicle showing my design therefor, the wiper being of indeterminate length and comprising a profile of flexible material;

FIG. 2 is a top rear end perspective view thereof;

FIG. 3 is a front elevational view thereof;

FIG. 4 is a rear elevational view thereof;

FIG. 5 is a end view thereof;

FIG. 6 is a top plan view thereof; and,

FIG. 7 is a bottom plan view thereof.
